UNITED STATES PATENT OFFICE.

SAMUEL S. MOISEVE AND JOSEPH S. MOISEVE, OF LOS ANGELES, CALIFORNIA.

TOY AEROPLANE.

Application filed March 17, 1923. Serial No. 625,741.

To all whom it may concern:

Be it known that we, SAMUEL S. MOISEVE and JOSEPH S. MOISEVE, both subjects of Russia, residing at Los Angeles, in the county of Los Angeles and State of California, have invented certain new and useful Improvements in Toy Aeroplanes, of which the following is a specification.

This invention relates to toy aeroplanes and the objects are first, to provide an aeroplane that may be mounted on the radiator cap of an automobile, or other moving object; second, to provide a toy aeroplane that will elevate and lower itself on a center-pole by the velocity of air passing the propeller and elevator thereof.

Further objects are to provide a toy aeroplane that is simple in construction and easy to install.

We attain these objects by the mechanism illustrated in the accompanying drawing, in which:

Figure 1 represents a side elevation of the aeroplane, in part section on line 1—1 of Figure 2.

Figure 2 represents a plan view of Figure 1.

Figure 3 represents a sectional view on line 3—3 of Figure 1.

Referring to the drawings in which like characters of reference designate similar parts, the port and starboard sides of the aeroplane are formed by the sides 1, which are separated by the blocks 11 and 10 positioned in the respective front and rear ends thereof, and a block 9 is secured between the said sides 1 at a point between the blocks 11 and 10 so as to form the tapered front and rear portions of the said fuselage with the customary general aeroplane lines. The slot 26 passes vertically through the central portion of the block 9, having tapered ends extending longitudinally towards the front and rear ends of the said block 9, beginning with a relatively small hole at the central point positioned between the bottom and top ends of the said slot 26.

The wing 2 is formed with the usual lines of an aeroplane and is secured to the central portion of the fuselage 1, between the nose and tail portions thereof, at right angles to the longitudinal line of the said fuselage, and an extension of the said slot 26 passes therethrough in line with the slot 26 in the block 9. The pole 6 passes operatively through the said slot 26 and is secured to a

movable base 32, and the springs 7 and 8 are secured to the lower and upper ends of the said pole 6 respectively. A frame 13 is secured in the front end of the fuselage 1 between the blocks 9 and 10, the shaft 12 passes operatively through the said block 10 longitudinally with the said fuselage 1, and is operatively held in one end of the frame 13, a propeller 5 is secured to the outer end of the shaft 12, and a pinion 15 is in turn secured to the inner end thereof, a shaft 17 is operatively positioned in the said frame 13 in line with the said shaft 12 a distance thereabove, a gear 14 is secured on the shaft 17 in mesh with the pinion 15 and a crank-shaft 20 is operatively secured in the frame 13, at right angles to the said shaft 17 a distance thereunder, and the crank 30 is integral with one side of the said crank shaft 20, the worm 18 is secured to the shaft 17 and the worm wheel 19 is secured to the crankshaft 20 in mesh with the said worm 18. The pin 22 is secured in the fuselage 1 between the plates 29 at a point between the blocks 9 and 11, the groove 25 is formed in the block 9 in line with the connecting rod 21, and the said connecting rod 21 is operatively positioned on the pin 22 and passes operatively through the grooves 25, the slot 28 passes through the front end portion of the said connecting rod 21, and the said crank 30 passes operatively through the said slot 28.

The rudder 3 is secured vertically on the upper face of the said block 11, and extends longitudinally with the said fuselage 1. The elevator 4 is positioned operatively around the rear end of the said fuselage 1 on the hinge 24, the pin 23 is secured in the opening 31 in line with the slots 27, the said slots 27 pass through the rear end of the plates 29, and the rear end of the connecting rod 21 is operatively connected to the said pin 23, by passing through an opening 31 in the said plate 29, and the said hinge 24 is secured to the lower face of the said block 11, as shown in Figure 1.

To operate our toy aeroplane the base 32 is moved forward, and the rudder 3 turns the aeroplane in the direction of travel, and the velocity of air passing through the propeller 5 turns the said propeller 5, the shaft 12 and the pinion 15, in the block 10 and frame 13, respectively, the said pinion 15 turns the gear 14, the shaft 17, the worm 18, the worm wheel 19, the crank shaft 20,

and the crank 30, respectively, in the frame 13, as the said crank 30 slides in the slot 28 and reciprocates the connecting rod 21 on the pin 22 so as to alternately lift and lower the pin 23 as the said crank 30 rises and falls in the slot 28, and the said pin 23 in turn lifts and lowers the front end of the elevator 4 on the hinges 24 at a reduced ratio to the revolutions of the said propeller 5, and intermediate speed reductions. When the front end of the said elevator 4 is turned to a raised position, the velocity of air passing thereunder drives the aeroplane ahead and provides pressure sufficient to overcome the weight of the said aeroplane, and will rise by sliding up to the spring 8 on the said pole 6 in the slot 26, and the front end of the said elevator 4 is then turned to a lowered position, as hereinbefore described, to allow the air current to pass thereover and depresses the said aeroplane to the spring 7, as hereinbefore described, and the rising and falling of the aeroplane is thus continued as long as the aeroplane is driven through the air, and the wing 2 in turn assists to reduce the weight of the aeroplane by the constant velocity of air passing thereunder and bears the aeroplane upwardly.

Having thus described our invention what we claim is:

1. A toy aeroplane of the class described, in combination with a fuselage; adapted to rise and fall on a pole passing through said fuselage; a propeller, adapted to turn by the velocity of air passing therethrough; an elevator; a power transmission means connected between the said propeller and elevator; and a rudder secured to the upper rear end of the said fuselage, as set forth.

2. A toy aeroplane of the class described, in combination with a fuselage; a wing se-

cured to the said fuselage; a pole, adapted to pass through the said fuselage and wing; a propeller, adapted to turn by the velocity of air passing therethrough; an elevator; a power transmission means connected between the said propeller and elevator; and a rudder secured to the upper-rear end of the said fuselage, as set forth.

3. A toy aeroplane of the class described, in combination with a fuselage; a wing secured to the said fuselage; a pole, adapted to pass through the said fuselage and wing; a cushion means secured to the upper and lower ends of the said pole; a propeller, adapted to turn by the velocity of air passing therethrough; an elevator; a power transmission means connected between the said propeller and elevator; and a rudder secured to the upper-rear end of the said fuselage, as set forth.

4. A toy aeroplane of the class described, comprising a fuselage, a rod on which said fuselage is mounted to rise and fall, a propeller shaft journaled on the fuselage, a propeller secured on said shaft, a pinion on said shaft, a worm shaft journaled on the fuselage, a gear on said worm shaft in mesh with said pinion, a worm on said worm shaft, a worm wheel shaft journaled in the fuselage, a worm wheel on said worm wheel shaft in mesh with said worm, a crank on said worm wheel shaft, a lever pivoted in said fuselage and provided with a slot in its forward end engaged by said crank, an elevator pivoted on the rear end of said fuselage and operatively connected to the rear end of said lever.

In testimony whereof we affix our signatures.

SAMUEL S. MOISEVE.
JOSEPH S. MOISEVE.
